(57) **CLAIM**

The ornamental design for a vehicle head light, as shown and described.

DESCRIPTION

FIG. 1 is a front elevational view of a vehicle head light showing our new design;

FIG. 2 is a perspective view thereof;

FIG. 3 is a side elevational view thereof;

FIG. 4 is a front elevational view of the left-handed version thereof;

FIG. 5 is a perspective view of the left-handed version thereof; and,

FIG. 6 is a side elevational view of the left-handed version thereof.

The broken line showing of the remainder of the vehicle front end is for illustrative purposes only and form no part of the claimed invention. The vehicle head light illustrated in FIGS. 1-3 is right-handed, and FIGS. 4-6 illustrate the left-handed version of the light having the same design.
